BOOT

George H. Bingham, Jr., Taneytown, Md.

Application March 9, 1951, Serial No. 14,448

Term of patent 7 years

(Cl. D7—4)

To all whom it may concern:

Be it known that I, George H. Bingham, Jr., a citizen of the United States of America, residing at Taneytown, county of Carroll, and State of Maryland, have invented a new, original, and ornamental Design for a Boot, of which the following is a specification, reference being had to the accompanying drawing forming a part thereof:

Figure 1 is a side elevation of a boot embodying my new design; and

Figure 2 is a front elevation thereof.

I claim:

The ornamental design for a boot, as shown.
